(75) Inventor: **Masao Tsuji**, Germantown, TN (US)

(57) **CLAIM**

(73) Assignee: **Hunter Fan Co.**, Memphis, TN (US)

The ornamental design for a combined motor housing, switch housing and blade irons unit for a ceiling fan, as shown and described.

(**) Term: **14 Years**

DESCRIPTION

(21) Appl. No.: **29/124,289**

FIG. 1 is a perspective view of a combined motor housing, switch housing and blade irons unit for a ceiling fan showing my new design;

(22) Filed: **Jun. 3, 2000**

FIG. 2 is an enlarged perspective view of the design shown in FIG. 1 with the environmental structure removed therefrom;

(51) LOC (7) Cl. **23-04**

FIG. 3 is a front view of FIG. 2;

(52) U.S. Cl. **D23/411**

FIG. 4 is a right-side view of FIG. 2;

(58) Field of Search **D23/377, 379,**

D23/385, 411; 446/5

FIG. 5 is a rear view of FIG. 2;

FIG. 6 is a left-side view of FIG. 2;

FIG. 7 is a top view of FIG. 2; and,

FIG. 8 is a bottom view of FIG. 2.

The broken line showing of environmental structure shown in FIG. 1 is for illustrative purposes only and forms no part of the claimed design.
